DIE FOR MAKING METAL FOIL LIDS

Walter S. Holmes, Toronto, Ontario, Canada, assignor, by
mesne assignments, to Reynolds Metals Company, Rich-
mond, Va., a corporation of Delaware

Filed July 11, 1960, Ser. No. 42,142

14 Claims. (Cl. 113—42)

This invention relates to a die for making lids of metal foil.

A disposable receptacle, having at its open end a peripheral outwardly extending lip, can be provided with a tightly fitting metal foil lid by making the lid with a dished central portion that fits snugly into the open end of the receptacle, and with an outer wall having an outwardly curled bead fitting under the lip. The formation of the lid can be performed in a sequence of operations, namely, dishing the central portion, then bending the peripheral portion inwardly to form the outer wall, and then forming the bead.

The object of this invention is to provide a die for performing these sequential operations.

A preferred embodiment of the invention will be described with reference to the accompanying drawings in which like reference numerals designate like parts and in which:

FIG. 1 is a perspective view of a plastic cup and a metal foil lid therefor, the lid being the product of the die illustrated in FIGS. 3 to 7 inclusive;

FIG. 2 is an enlarged longitudinal sectional view through the cup and lid of FIG. 1, the bottom of the cup being broken away;

FIG. 2a is a further enlarged fragmentary sectional view of the assembled cup and lid;

FIG. 3 is a partly sectional, somewhat diagrammatic side view of a die constructed in accordance with the present invention for forming the metal foil lid of FIGS. 1 and 2, the upper assembly of the die being in its uppermost position;

FIG. 4 is a view similar to FIG. 3 but showing the upper die assembly moving downwardly;

FIG. 5 is a view similar to FIGS. 3 and 4 but showing the upper die assembly in its bottom position;

FIG. 6 is a view similar to FIGS. 3, 4 and 5 but showing the upper die assembly moving upwardly; and

FIG. 7 is an enlarged fragmentary sectional view of the bead curling portion of the die when in the position of FIG. 6.

FIGS. 1, 2 and 2a illustrate a cup 10 and a lid 20 for the cup. Neither the cup nor the lid forms part of the present invention. However an understanding of a suitable configuration of the lid will facilitate the description of the die for making it. The lid will be described with reference to a cup on which it fits.

The cup 10 has a side wall 11 that flares outwardly from the bottom of the cup to the open end or mouth 12 of the cup. At the mouth the wall 11 has a smooth inner annular wall surface 13, and the wall curves upwardly and outwardly to an upper circular edge 14 concentric with the surface 13, and then curves downwardly and outwardly to a peripheral outwardly extending lip 15 also concentric with the surface 13 and edge 14. The lip 15 is preferably stiff, so that it does not easily bend inwardly. While a great variety of materials may be used for the cup 10, the cup may for example be made of thin impact extruded plastic, such a cup being competitive in cost of manufacture with a cardboard cup.

The lid 20 consists of metal foil and has a generally horizontal circular bottom 21 provided with a raised ornamental pattern 22. At the center of the lid is an opening 23 to permit egress and inflow of air from and to the

2

cup 10 when the lid is put on and removed. However as shown in FIG. 2 the metal 23a displaced in forming the opening 23 extends downwardly around the opening. Around the bottom 21 the lid has an inner upwardly extending wall 24. The inner wall 24 flares outwardly slightly and has an outer annular surface 25 which conforms as closely as possible to the inner annular wall surface 13 of the cup. From the upper edge of the wall 24 a rim 26 extends outwardly so as to engage the upper edge 14 of the cup. Extending downwardly from the rim 26 is a peripheral outer wall 27 which terminates in a stiffening bead 28. The bead 28 curls outwardly from a circle 29 at the inner surface of the outer wall 27, the circle 29 when the lid is in place on the cup being concentric with the lip 15 of the cup but a little below the lip. The circle 29 is coplanar with and concentric with the center line of the bead. In the manufacture of the lid the diameter of the circle 29 is made slightly less than the diameter of the lip 15 so that the inner circumference of the wall 27 at this circle is normally slightly smaller than the circumference of the lip 15. When the lid is pressed onto the cup, the wall 27 and bead 28 must expand to pass over the lip, but being of metal, and thus resilient, they pull inwardly again when they have passed over the lip, and thus the bead engages under the lip and pulls the lid down onto the cup, holding the outer annular surface 25 of the lid's inner wall 24 in intimate contact with the inner annular wall surface 13 of the cup and holding the rim 26 of the lid in intimate contact with the upper edge of the cup. The rim limits the downward movement of the lid on the cup and thus ensures that the bead is properly positioned relatively to the lip 15, i.e., with the circle 29 slightly lower than the lip. The stiffening bead 28, pulling inwardly below the lip 15, prevents accidental upward movement of the lid from the position of FIG. 2a. Thus, with the bead 28 forced over the lip 15, the cup is clasped between the bead 28 and the rim 26. The inward pull of the bead also provides a transverse clamping action between the lid wall 27 outside the cup and the lid wall 24 inside the cup. Thus it is desirable for the inner wall 24 to extend downwardly from the rim 26 at least as far as the plane of the circle 29, and in the lid illustrated the wall 24 is deeper than the outer wall 27 so as to obtain a large contact area between the outer surface 25 and the cup surface 13. Such a deep inner wall 24 helps to prevent sloshing of liquid out of the cup even if the lid is not pulled tightly down against the upper edge 14 of the cup.

An important advantage of having the bottom 21 and wall 24 of the lid nested snugly in the mouth of the cup is that they reinforce and strengthen the cup against transverse pressure that may be applied by someone gripping the cup or by accidental forces to which the cup may be subjected. Not only does the reinforcing action help to prevent accidental breakage of the cup before the lid is removed, but it helps to prevent accidental dislodgment of the lid, particularly with flexible walled cups. A flexible walled cup under transverse pressure tends to change from a circular to an oval shape, and a circular lid that grips the cup around merely the outer periphery of the cup, rather than extending down into the cup as do the wall 24 and bottom 21, may pop off the cup rather than prevent the deformation of the cup to oval shape.

As will be explained, the lid 20 is formed from a flat circular blank of metal foil. In forming the inner wall 24, rim 26 and outer wall 27 it is necessary to dispose of excess foil. This might be done by forming regular radial pleats in the foil, but in order to obtain good contact between the surfaces of the lid and cup it is desirable to have the lid walls as smooth as possible, without radial passageways between the lid and cup through which the

contents of the cup may leak. Accordingly, in the manufacture of the lid such gathering of the foil as cannot be avoided is allowed to take place in an irregular manner (i.e. without deliberate pleating) but the gatherings are scattered as uniformly as possible over the lid portions 24, 26, 27 so that very small wrinkles 30 are formed, the wrinkles being generally radial but nonetheless irregular. Thus, with the bead holding the lid down on the cup, there is substantially a seal around the mouth of the cup, and if the cup is inverted there is no loss of its contents.

Since the outer wall 27 and bead 28 are resiliently expansible circumferentially, the lid can be removed from the cup by an upward pull on the bead. If the bead were not provided, there would be insufficient friction between the surfaces of the cup and lid to prevent accidental displacement of the lid from the cup. The fact that the bead curls outwardly from the wall 27 ensures that as the lid is placed on and removed from the cup there is no tendency for the bead to be caught and torn open by the lip 15.

Whereas with paper cups and lids a paper taste is sometimes imparted to the contents of the cups, particularly if the contents are hot, the foil lid 20 does not affect the flavour of the contents, and the lid 20 can be used on a cup of plastic which also does not affect the flavour. The foil lid 20 has low heat emissivity and high heat reflectivity, and can be used on a cup 10 of foamed plastic having excellent heat insulative properties so that the cup and lid are far superior to conventional paper cups and lids in holding their contents at a constant temperature. The foil has the further advantage of being hydrophobic; it does not absorb and retain the liquid in the cup, nor become soggy, and it consequently provides a useful dish into which the cup may be set to prevent any liquid that runs down the cup from wetting a surface on which the lid is placed.

The metal 23a extending downwardly around the opening 23 forms a frustro-conical baffle which helps to prevent liquid within the cup from sloshing out through the opening. The effective area of the opening through the lid to allow passage of air should be equivalent to a circular hole of a diameter not less than approximately 0.03 inch; too small an opening through the lid appears, particularly with smooth surfaced cups, to promote leakage around the edge of the cup. To prevent loss of liquid from the cup the equivalent hole diameter should not exceed approximately 0.07 inch.

Metal up to about 0.006 inch in thickness is ordinarily considered to be foil, and while thick foil can be used to make the lid 20 it is preferred to use as thin a gauge of foil as possible in order to keep the cost of the lid to a minimum. Aluminum foil half hard in temper, or harder, is preferred. Such aluminum foil down to about 0.001 inch thickness has sufficient strength, and it is preferred not to exceed 0.0025 inch in thickness. Thin foil has the advantage that it can easily be marked. For example, the lid of a cup of coffee can be indented, by means of a pencil or similar instrument, with the letters C, S or B to designate a cup containing, respectively, coffee with cream, coffee with sugar, or black coffee, or the lid may be made with such letters embossed or indented therein so that the user can encircle the letter or letters appropriate to identify the contents of the cup. Another advantage of thin foil is that it can be substantially consumed or destroyed in an incinerator, whereas heavier metal creates a disposal problem.

In a specific example, for a cup having a wall thickness of 0.017 inch and a lip 15 of $2\frac{1}{8}$ inch diameter, an aluminum foil lid of 0.0018 inch thickness was used, having a bead 28 curled on a $1\frac{1}{16}$ inch outside diameter, and having for the circle 29 in undeformed diameter 0.004 inch less than the diameter of the lip 15. This difference in diameters can vary from about 0.001 inch to about 0.008 inch for a cup lip having approximately the

diameter mentioned. Buckling of the bottom 21 and wall 24 of the lid, as the bead passes over the lip 15, is prevented by the flexibility of the rim 26 and by the fact that the outer surface 25 of the wall 24 conforms in diameter to the inner surface 13 of the cup.

The die of FIGS. 3 to 7, and the operation of the die, will be described in detail below, but the formation of the lid 20 in the die can be seen from a brief inspection of FIGS. 3 to 7. The sequence of operations of the die is from the fully open position of FIG. 3 through the partly closed position of FIG. 4 to the fully closed position of FIG. 5 and then back through the partly closed position of FIG. 6 to the fully open position of FIG. 3. As the die closes from the fully open position of FIG. 3, a flat circular blank is severed from a sheet 32 of metal foil, and the central portion of the blank is dished to the shape shown in FIG. 4 to form the inner lid wall 24 and bottom 21. During the dishing operation the peripheral portion 33 of the blank is pulled inwardly around the central portion 34. As the peripheral portion is pulled inwardly, it is smoothly and uniformly gripped between the plane end surfaces of gripping rings 60 and 130 of FIGS. 3 and 4, the pressure exerted on the gripped peripheral portion being sufficiently light that the peripheral portion can slip inwardly without tearing as the blank is dished. Inward slipping of the peripheral portion is essential during the dishing of the central portion since foil cannot stretch or draw appreciably without tearing. The uniform pressure around the peripheral portion ensures that the wrinkling of the foil caused by the dishing of the central portion is irregular but generally radial and scattered all around the inner wall 24 and peripheral portion 33, as already described.

During the movement of the die from the position of FIG. 4 to that of FIG. 5 the peripheral portion 33 is bent inwardly, as shown in FIG. 5, to form the outer wall 27 of the lid, the rim 26, and the annular recess 35 between the dished central portion 34 and the peripheral portion 33. During the return movement of the die from the position of FIG. 5 to that of FIG. 6, the stiffening bead 28 is formed by curling the edge of the peripheral portion outwardly and then inwardly through approximately 360 degrees, as shown in FIGS. 6 and 7. The completed lid 20 can then be removed as the die returns to the fully open position of FIG. 3.

Now considering the die construction in detail, an upper die assembly 36 is, as shown in FIG. 3, normally spaced from a lower die assembly 37, being reciprocable downwardly (the forward movement) and upwardly (the return movement) by any conventional means, for example by a flywheel and crankshaft (not shown). The components of the upper die assembly are mounted on an upper die block 38, and include a downwardly facing female punch 40. The main body 41 of the female punch 40 is fixed to the underside of the die block 38 by studs 42, but the punch also includes a knockout 43 which can be depressed downwardly with respect to the punch body 41. The knockout has a head 44 the lower surface 45 of which forms part of the face of the punch. A plunger 46 fast with the head 44 extends slidably upwardly through aligned passages 47 in the body 41 and die block 38, and the plunger protrudes from the top of the die block where the a collar 48 is fastened to it. A spring 49 in compression between the collar 48 and the die block normally prevents the knockout from moving downwardly relatively to the die block 38 and punch body 41.

The female punch 40 has a peripheral end wall 50 defining a recess 51 in the face of the punch. The bottom surface 45, 52 of the recess corresponds in shape to the outer surface of the bottom 21 of the lid to be formed, ridges 53 being provided on the knockout corresponding to the pattern 22 on the bottom of the lid. A central cylindrical opening 54 is provided for formation of the opening 23 and metal baffle 23a of the lid, as will be

described. The inner surface 55 of the end wall 50 corresponds in shape to the outer surface 25 of the inner wall 24 of the lid, that is to say, it corresponds in shape to the cup's inner annular wall surface 13 against which the wall 24 is to fit snugly. The downwardly facing end surface 56 of the wall 50 corresponds in shape to the undersurface of the rim 26 of the lid, and the outer surface 57 of the wall 50 and of the female punch corresponds in shape to the inner surface of the outer wall 27 of the lid. Spaced back from its lower end the punch 40 has an upwardly facing annular peripheral ledge surface 58.

Around the punch 40 and spaced therefrom is a first cylindrical gripping ring 60. The gripping ring 60 is an integral part of and protrudes downwardly from a die member 61 which is held between the punch body 41 and die block 38 by the studs 42, and the gripping ring 60 is therefore fixed in position relatively to the female punch. The gripping ring 60 has a downwardly facing end surface 62 in a horizontal plane to which the end surface 56 of the punch extends. As will be explained, the outer edge 63 of the surface 62 acts as a foil severing edge. Above the edge 63 the gripping ring has an inward bevelled jog 64.

Around the female punch 40 and within the gripping ring 60 is a first cylindrical pressure ring 70 slidable longitudinally of the punch. The pressure ring 70 is urged downwardly in the direction of the end of the punch 40 by springs and plungers, a typical spring 71 and plunger 72 being illustrated. The plunger 72 is slidable vertically in a cylindrical passage 73 through the die member 61 and rests at its lower end on the pressure ring 70. At its upper end the plunger has a head 74 that travels in a cylindrical passage 75 through the die block 38. The upper end of the passage 75 is closed by a plug 76 fixed to the die block 38, the plug having a vent 77 from the passage 75 to atmosphere. The spring 71 is in compression between the plug 76 and head 74 and normally, as shown in FIG. 3, the pressure ring is held in the position where a downwardly facing ledge surface 78 of the ring abuts against the ledge surface 58 of the female punch, the ledge surface 58 constituting a stop which limits downward movement of the first pressure ring relatively to the punch. It will be seen from FIG. 3 that with the pressure ring 70 in its lowermost position relatively to the punch 40, the downwardly facing end surface 79 of the ring is stepped back (upwardly) from the end surface 56 of the punch end wall 50 and from the end surface 62 of the first gripping ring 60.

The lower end of the pressure ring 70 is shown greatly enlarged in FIG. 7, from which it will be seen that the ring 70 fits very closely around the female punch 40, the clearance between the inner surface 80 of the ring 70 and the outer surface 57 of the punch 40 being less than the thickness of the foil 32. The lower end surface 79 of the ring 70 is plane and horizontal, but in this surface is provided a downwardly facing smooth annular recess 81 around the female punch. As seen in FIG. 7, the recess 81 is semi-circular in cross-section and with the surface 80 it defines an annular knife edge 82 adjacent the outer surface 57 of the female punch.

Referring again to FIG. 3, the upper die assembly 36 includes a stripper plate 90 around the first gripping ring 60. The stripper plate 90 is normally suspended from the die block 38 by plungers, one of which is illustrated at 91. The plunger 91 is fixed to the stripper plate, through a cylindrical passage 92 in the die block, and has a head 93 that travels in a larger cylindrical die block passage 94 coaxial with the passage 92. The stripper plate is pressed downwardly by springs, one of which is shown at 95. The spring 95 is in compression between the stripper plate 90 and die block 38, and the plunger head 93 normally rests against the step 96 in the die block between the passages 92 and 94. In this position

the plane lower surface 97 of the stripper plate is lower than the end surface of the first gripping ring.

Let us now consider the lower die assembly 37. This assembly has a stationary bed consisting of two blocks 100 and 101 resting on and fixed to a third block 102. The bed has a stepped cylindrical opening 103 through the block 100 and coaxial with the female punch 40, with the first gripping ring 60 and with the first pressure ring 70 of the upper die assembly. Around the upper circular edge 104 of the opening 103 the bed has a plane upper surface 105 on which the sheet of metal foil 32 lies between the die assemblies. The sheet 32 must be sufficiently large to cover the opening 103. The block 101 is secured at the bottom of the opening 103 with its upper surface 106 well below the level of the foil receiving surface 105.

Located in and coaxial with the opening 103 is a male forming punch 110 having a head 111 and integral stem 117. The head 111 has an upwardly facing surface 112 complementary to the surface 45, 52 of the female punch 40, having recesses 112a corresponding to the ridges 53 for forming the lid pattern 22. A conical pin 113 pointing upwardly from the center of the surface 112 is adapted to register with the opening 54 in the female punch. The head 111 has an outwardly facing surface 114 complementary to the surface 55 of the female punch but six foil thicknesses smaller in diameter, for a reason which will be explained. Below the surface 114 the head has a peripheral flange 115 which provides a downwardly facing ledge surface 115a and an upwardly facing ledge surface 115b opposite the surface 56 of the female punch.

The stem 117 of the male punch is slidable vertically in a cylindrical passage 116 through the bed block 101, and the stem has at its lower end a collar 117a travelling in aligned cylindrical passages 118, of greater diameter than the passage 116, in the blocks 101 and 102. In its vertical sliding the male punch 110 is guided not only by its stem 117 but also by a vertical cylindrical pin 119 screwed or pressed into the underside of the head 111 and guided by the cylindrical wall of a vertical passage 120 through the bed block 101. The pin 119 prevents the punch 110 from rotating on a vertical axis, and thus ensures that the recesses 112a register with the ridges 53 on the knockout, the latter being prevented from rotating by a similar vertical pin (not shown) fixed to the knockout and extending upwardly into a passage (not shown) through the body 41 of the female punch.

The male punch 110 is urged upwardly by springs and plungers acting on the underside of the head 111, one such spring 122 and plunger 123 being illustrated. The plunger 123 is slidable vertically in a cylindrical passage 124 through the bed block 101 and has at its lower end a head 125 that travels in a cylindrical passage 126 through the bed block 102. The lower end of the passage 126 is closed by a plug 127 fixed to the bed block 102, the plug having a vent 128 from the passage 126 to atmosphere. The spring 122 is in compression between the plug 127 and plunger head 125, and normally holds the male punch 110 in its uppermost position where, as shown in FIG. 3, the collar 117a abuts against the step 129 between the passages 116 and 118, the upper surface 112 of the male punch being, at this uppermost position, lower than the foil receiving surface 105 of the bed.

Within the bed opening 103 and around the male punch 110 but spaced therefrom is a second cylindrical gripping ring 130 having a plane horizontal upper end surface 131 directly below and of the same inner diameter as the end surface 62 of the first gripping ring 60. The second gripping ring is urged upwardly by cylindrical plungers, one of which is shown at 132, in turn urged upwardly by a platform 133 and a spring 134. The upper end of the plunger 132 engages the underside of the ring 130, and the plunger extends vertically down-

wardly through a cylindrical passage 135 through the bottom bed block 102. The lower end of the plunger 132 rests on the horizontal platform 133 which is slideable vertical on a rod 136 screwed at 136a into the underside of the bed block 102. A boss 137 on the platform around the rod 136 helps to guide the platform on the rod. The platform 133 is urged upwardly by the spring 134 which is in compression between the underside of the platform and a footing (not shown).

The second gripping ring 130 has on its inner surface an upwardly facing annular ledge surface or rest 138, and on this rest a second pressure ring 140 is normally supported by a downwardly facing annular ledge surface or stop 141 on the outer surface of the ring 140. On its inner surface 142 the ring 140 has an upwardly facing ledge surface or stop 143 which, in the normal position shown in FIG. 3, engages the downwardly facing ledge surface 115a of the male punch 110. Thus the limit of upward movement of the rings 130 and 140, under the upward urging of the spring 134, is determined by the uppermost position to the surface 115a of the male punch, as well as by the engagement of the boss 137 with the underside of the bed block 102. In the uppermost position of the ring 130 its end surface 131 is coplanar with the upper surface 105 of the bed and is thus higher than the male punch.

The upper end of the second pressure ring 140 is best shown in FIG. 7. The upwardly facing end surface 144 of the second pressure ring is directly below the downwardly facing end surface 79 of the first pressure ring 70, and the pressure rings have the same outside diameter. A short distance inwardly from its outer edge the surface 144 is stepped downwardly, as at 144a, by an amount slightly exceeding three times the thickness of the foil 32, for a reason which will be explained when the operation of the die is discussed. When the second pressure ring is in its uppermost position (FIG. 3), the highest part of the surface 144 (at the outer edge) is coplanar with the surfaces 131 and 105. As shown in FIG. 7, the surface 144 has at its inner edge an annular ledge which is of ogee shape in cross-section, the ogee shape being concave at its top 144b adjacent the first pressure ring, and smoothly convex at the bottom 144c adjacent the female punch 40 where it merges with the inner surface 142 of the second pressure ring.

The operation of the die will now be described in detail. The upper die assembly 36 moves downwardly from the position shown in FIG. 3, and as it does so the lower surface 97 of the stripper plate 90 comes into contact with the foil sheet 32 lying on the bed surface 105. The spring 95 compresses and under its force the stripper plate holds the foil sheet against the bed. As the upper die assembly moves further downwardly, the smooth end surfaces 62 and 131 of the gripping rings 60 and 130 cooperate, under the force of the spring 134, to grip between them, as a flat circular blank, that portion of the foil sheet that is bounded by the upper edge 104 of the opening 103. The descending ring 60 cooperates at its outer edge 63 with the edge 104 to sever the flat circular blank from the sheet 32. The second gripping ring 130 is forced by the descending ring 60 to retract downwardly against the force of the spring 134, and the second pressure ring 140, which merely rests gravitationally on the rest 138, moves downwardly with the ring 130. Since the end surface 62 of the ring 60 is coplanar with the downwardly facing end surface 56 of the female punch 40, the surface 56 contacts the upper surface of the foil simultaneously with the surface 62. As the upper die assembly descends, the flat foil blank, gripped between the rings 60 and 130, comes into contact with the upper surface 112 of the male punch 110. The spring 122 which urges the male punch upwardly is stiff and has sufficient force to sustain the male punch in its uppermost position until the upper die assembly reaches the position of FIG. 4. Thus, although the gripping ring 130 and the pres-

sure ring 140 slide downwardly in the opening 103, the male punch is sustained to protrude beyond the end surfaces 131 and 144 of these retracting rings, and the male punch presses the foil blank into the recess 51 of the female punch and against the surfaces 45, 52, 55 and 56, as shown in FIG. 4. The conical pin 113 pierces the foil and protrudes into the opening 54, pushing some of the foil upwardly into the opening 54 and forming the opening 23 and baffle 23a in the foil. The large spring 134 is relatively weak, and during the dishing of the central portion 34 of the foil blank into the recess 51 the spring causes the gripping rings 60 and 130 to exert sufficiently light force on the peripheral portion 33 to permit the latter to slip from between the plane end surfaces 62 and 131 of the gripping rings and wrinkle generally radially, as already described, without tearing. The coplanar surfaces 56 and 62 ensure that the peripheral portion slips straight out from between the surfaces 62 and 131 in a direction normal to the vertical axis of the die.

At the position of FIG. 4 the peripheral portion 33 of the blank has completely slipped out of the grip of the gripping rings, but the blank is now firmly held between the male and female punches which tend to press flat the wrinkles in what will be the wall 24 and rim 26 of the finished lid. It has been stated that the surface 114 of the male punch 110 has a diameter six foil thicknesses smaller than the surface 55 of the female punch. Thus, as indicated in FIG. 7, there is a clearance of three foil thicknesses between the surfaces 55 and 114 when the punches are in full engagement, this clearance providing room for the wrinkles 30 and permitting the punches to cooperate fully in forming the pattern 22 in the bottom of the lid.

In the downward movement to the position of FIG. 4 the upper surface 144 of the second pressure ring 140 has not protruded above the plane end surface 131 of the second gripping ring 130, the ring 140 having descended with the rest 138. Thus the ring 140 does not interfere with the slipping of the peripheral portion of the blank from between the gripping rings. However, with the blank now free of the gripping rings, and the central portion of the blank pressed fully into the recess 51 of the female punch, the downward descent of the ring 140 is stopped by the upper surface 106 of the bed block 101. Continued downward movement of the upper die assembly to its bottom position, shown in FIG. 5, further retracts the gripping ring 130 downwardly against the force of the spring 134, and the female punch 40 forces the male punch 110 to retract downwardly against the force of the spring 122. Thus the pressure ring 140 presses the wrinkled peripheral portion of the foil blank upwardly against the outer surface 57 of the female punch.

The inner surface 142 of the ring 140 is complementary to and slideable over the outer surface 57 of the female punch. As indicated by FIG. 7, the clearance between the surfaces 57 and 142 slightly exceeds three times the thickness of the foil 32. Thus, although wrinkles 30 may cause parts of the peripheral portion 33 of the blank to be three times foil thickness, these wrinkles do not cause seizure and tearing of the peripheral portion between the relatively moving surfaces 57 and 142. As previously mentioned, the end surface 144 is also stepped downwardly, as at 144a, by an amount slightly exceeding three times foil thickness. This is done to prevent pinching of the wrinkled peripheral portion between the pressure rings 70 and 140, for as the upper die assembly moves downwardly from the position of FIG. 4 to its bottom position, FIG. 5, the non-retracting ring 140, resting against the stop 106, engages the end surface 79 of the ring 70 before the peripheral portion has been completely moved from between the rings 70 and 140. However as seen in FIG. 7, engagement of the rings 70 and 140 can only take place near the outer edges of the end surfaces 79 and 144, and after such engage-

ment but prior to the arrival of the upper die assembly at the position of FIG. 5 the part of the wrinkled peripheral portion 33 not yet pressed against the outer wall 57 of the descending female punch extends into the clearance between the ends of the rings 70 and 140. By way of example, for a foil thickness of 0.0018 inch, a clearance of 0.0060 inch is satisfactory between the surfaces 79 and 144a and between the surfaces 57 and 142.

The engagement of the rings 70 and 140 forces the ring 70 to remain stationary as the upper die assembly finishes its movement downwardly to the position of FIG. 5; the ring 70 thus retracts relatively to the female punch 40 against the force of the spring 71, which compresses. In the position of FIG. 5 the ring 70, held upwardly relatively to the punches, has its knife edge 82 positioned higher than the edge of the foil. As seen in FIG. 7, the recess 81 defines with the ogee shaped surfaces 144b and 144c a cavity 150 of substantially the shape desired for the bead 28, the cavity being open towards the outer surface 57 of the female punch below the knife edge 82.

The bottom position of FIG. 5 having been reached, the upper die assembly now begins to move upwardly. On the upward or return movement of the upper die assembly, from the position of FIG. 5 to that of FIGS. 6 and 7, the spring 71 is able to expand from its compressed condition and it holds the ring 70 in engagement with the ring 140 and the ring 140 against the stop 106. However the spring 122 moves the male punch 110 upwardly with the female punch 40, and thus the edge of the foil is forced against the knife edge 82 which turns the foil into the cavity 150. By the time the position of FIGS. 6 and 7 has been reached, the punches, gripping the foil, have moved sufficiently far upwardly relatively to the pressure rings 70 and 140 that the edge of the foil has been forced to curl outwardly and then inwardly through 360 degrees, and the bead 28 is thus formed, completing the lid.

The spring 134 moves the gripping ring 130 upwardly, following the gripping ring 60, and at the position of FIG. 6 the rest 138 is brought into engagement with the ledge surface 141 of the pressure ring 140. At the same time the ledge surface 58 of the female punch engages the surface 78 of the pressure ring 70, and consequently the rings and punches all rise until they are restored to their normal positions of FIG. 3. The bevelled jog 64 (on the ring 60) and the stripper plate 90 ensure that the rising ring 60 does not foul the sheet 32. The pressure ring 140 during the last part of its upward travel presses the completed lid by its bead off the male punch 110, and the lid is freed from the female punch by a downward tap on the plunger 46 of the knockout 43. The lid may then be blown from between the die assemblies by a blast of air. The foil sheet 32 is shifted on the bed to bring another portion over the opening 103, and the operation of the die is repeated.

It will be understood that the form of the invention herewith shown and described is a preferred example and various modifications can be carried out without departing from the spirit of the invention or the scope of the appended claims.

What I claim as my invention is:

1. A die for making a lid from a blank of metal foil, comprising a first die assembly and a second die assembly normally spaced from the first, the die assemblies having a forward and return movement, the first die assembly including a female forming punch having a peripheral end wall defining a recess at the face of the punch, the wall having an inner surface, an end surface and an outer surface, and a first pressure ring around and slidable relative to the female punch along the outer surface of the female punch, the second die assembly including a male forming punch cooperable with the female punch on forward movement of the die assemblies to press the central portion of the blank into the

recess thus pulling the peripheral portion of the blank inwardly, and a second pressure ring around the male punch, the pressure rings having engageable end surfaces, the second pressure ring being slidable relatively to the female punch along the outer surface of the female punch in a direction away from the end surface of the peripheral wall to press the peripheral portion of the blank against said outer surface while the male punch holds the central portion in the recess of the female punch, means positioning the second pressure ring on forward movement of the die assemblies to achieve sliding of the second pressure ring relative to the female punch along the outer surface of the female punch, in said direction, only after the central portion of the blank has been pressed fully into the recess of the female punch, the first pressure ring having a foil catching edge adjacent said outer surface for curling the edge of the blank outwardly from said outer surface, said foil catching edge when the end surfaces of the pressure rings are engaged defining with the second pressure ring a foil curling cavity for forming an outwardly cured stiffening bead on the peripheral portion of the blank while the male punch holds the central portion in the recess, and means positioning the pressure rings to achieve sliding thereof relative to the female punch along the outer surface of the female punch in a direction opposite to said direction to catch and curl the edge of the blank after the pressing of the peripheral portion of the blank against said outer surface.

2. A die as claimed in claim 1, including means for limiting movement of the first pressure ring along the female punch towards said end surface of said wall whereby the first pressure ring is always stepped back relative to said end surface, and means outside the pressure rings for gripping the peripheral portion of the blank in a slip grip under which the peripheral portion is pulled inwardly and wrinkles generally radially without tearing as the central portion of the blank is pressed into the recess.

3. A die as claimed in claim 2, wherein first spring means urge the male punch towards the female punch, and after the central portion of the blank has been pressed into the recess of the female punch the latter on continued forward movement of the die assemblies retracts the male punch against the force of the first spring means, the positioning means for the second pressure ring preventing retraction of the second pressure ring with the male punch whereby the second pressure ring presses the peripheral portion of the blank against the outer surface of the female punch.

4. A die as claimed in claim 3, wherein the positioning means for the pressure rings include second spring means urging the first pressure ring towards the second pressure ring, the second pressure ring when prevented from retracting on forward movement of the die assemblies being stationary forcing the first pressure ring to retract against the second spring means, and the second spring means on initial return movement of the die assemblies holding the first pressure ring in stationary engagement with the second pressure ring while the first spring means move the male punch from retracted position thus forcing the edge of the blank against the foil catching edge and into the foil curling cavity.

5. A die for making a lid from a blank of metal foil, comprising a first die assembly and a second die assembly normally spaced from the first, the die assemblies having a forward and return movement, the first die assembly including a female forming punch having a peripheral end wall defining a recess at the face of the punch, the wall having an inner surface, an end surface and an outer surface, and a first pressure ring around and slidable relative to the female punch along the outer surface of the female punch, the second die assembly including a male forming punch cooperable with the female punch on forward movement of the die assemblies

11

to press the central portion of the blank into the recess thus pulling the peripheral portion of the blank inwardly, and a second pressure ring around the male punch, the pressure rings having engageable end surfaces, the second pressure ring being slideable relative to the female punch along the outer surface of the female punch in a direction away from the end surface of the peripheral wall to press the peripheral portion of the blank against said outer surface while the male punch holds the central portion in the recess of the female punch, means positioning the second pressure ring on forward movement of the die assemblies to achieve sliding of the second pressure ring relative to the female punch along the outer surface of the female punch, in said direction, only after the central portion of the blank has been pressed fully into the recess of the female punch, the first pressure ring having a foil catching edge adjacent said outer surface for curling the edge of the blank outwardly from said outer surface, said foil catching edge when the end surfaces of the pressure rings are engaged defining with the second pressure ring a foil curling cavity for forming an outwardly curled stiffening bead on the peripheral portion of the blank while the male punch holds the central portion in the recess, and means positioning the pressure rings to achieve sliding thereof relative to the female punch along the outer surface of the female punch in a direction opposite to said direction to catch and curl the edge of the blank after the pressing of the peripheral portion of the blank against said outer surface, the first die assembly including a first gripping ring around the first pressure ring and the second die assembly including a second gripping ring around the second pressure ring, the gripping rings having end surfaces cooperable on forward movement of the die assemblies to grip the peripheral portion of the foil blank in a slip grip under which the peripheral portion is pulled inwardly without tearing, the positioning means positioning the pressure rings, during the aforesaid gripping and pressing of the blank into the recess of the female punch, with the second pressure ring not protruding beyond the end surface of the second gripping ring and the first pressure ring not protruding beyond the end surface of the first gripping ring, the first gripping ring being fixed relative to the female punch, and spring means urging the second gripping ring towards the first gripping ring, the second gripping ring being slideable longitudinally of the second pressure ring, the spring means having sufficiently light force to permit the peripheral portion of the blank to slip from between the end surfaces of the gripping rings when the central portion is being pressed into the recess of the female punch.

6. A die as claimed in claim 5, wherein the spring means normally position the second gripping ring with its end surface protruding beyond the male punch.

7. A die as claimed in claim 6, wherein the end surface of the first gripping ring is coplanar with the end surface of the end wall of the female punch.

8. A die as claimed in claim 7, wherein, as the central portion of the blank is pressed into the recess of the female punch, the first gripping ring retracts the second gripping ring against the force of the spring means whereby the male punch protrudes beyond the end surface of the retracting second gripping ring.

9. A die for making a lid from a blank of metal foil, comprising a first die assembly and a second die assembly normally spaced from the first, the die assemblies having a forward and return movement, the first die assembly including a female forming punch having a peripheral end wall defining a recess at the face of the punch, the wall having an inner surface, an end surface and an outer surface, and a first pressure ring around and slideable relative to the female punch along the outer surface of the female punch, the second die assembly including a male forming punch cooperable with the female punch on forward movement of the die assem-

12

bles to press the central portion of the blank into the recess thus pulling the peripheral portion of the blank inwardly, and a second pressure ring around the male punch, the pressure rings having engageable end surfaces, the second pressure ring being slideable relative to the female punch along the outer surface of the female punch in a direction away from the end surface of the peripheral wall to press the peripheral portion of the blank against said outer surface while the male punch holds the central portion in the recess of the female punch, means positioning the second pressure ring on forward movement of the die assemblies to achieve sliding of the second pressure ring relative to the female punch along the outer surface of the female punch, in said direction, only after the central portion of the blank has been pressed fully into the recess of the female punch, the first pressure ring having a foil catching edge adjacent said outer surface for curling the edge of the blank outwardly from said outer surface, said foil catching edge when the end surfaces of the pressure rings are engaged defining with the second pressure ring a foil curling cavity for forming an outwardly curled stiffening bead on the peripheral portion of the blank while the male punch holds the central portion in the recess, and means positioning the pressure rings to achieve sliding thereof relative to the female punch along the outer surface of the female punch in a direction opposite to said direction to catch and curl the edge of the blank after the pressing of the peripheral portion of the blank against said outer surface, the second pressure ring having, for defining the foil curling cavity, a smooth annular recess which surrounds the female punch when the end surfaces of the pressure rings are engaged, said recess being defined by a surface of the second pressure ring that is ogee shaped in cross-section, the ogee shaped surface being smoothly convex adjacent the female punch and concave adjacent the first pressure ring when the end surfaces of the pressure rings are engaged.

10. A die as claimed in claim 9, wherein the foil catching edge is a knife edge defined by a smooth annular recess around the female punch in the first pressure ring, the latter recess cooperatnig with the recess in the second pressure ring to define the foil curling cavity.

11. A die as claimed in claim 10, wherein the foil catching edge of the first pressure ring is closer than the thickness of the foil to the outer surface of the female punch.

12. A die as claimed in claim 11, wherein the second pressure ring is slideable relatively to the female punch over the outer surface of the female punch with a clearance slightly exceeding three times the thickness of the foil to accommodate wrinkles in the foil.

13. A die as claimed in claim 12, wherein the pressure rings engage each other near the outer edges of their end surfaces and have between their end surfaces, inwardly of where they engage, a clearance slightly exceeding three times the thickness of the foil so as not to pinch wrinkles in the peripheral portion of the blank as it is pressed against the outer surface of the female punch.

14. A die for making a lid from a blank of metal foil, comprising a first die assembly and a second die assembly normally spaced from the first, the die assemblies having a forward and return movement, the first die assembly including a female forming punch having a peripheral end wall defining a recess at the face of the punch, the wall having an inner surface, an end surface and an outer surface, and a first pressure ring around and slideable relative to the female punch along the outer surface of the female punch, the second die assembly including a male forming punch cooperable with the female punch on forward movement of the die assemblies to press the central portion of the blank into the recess thus pulling the peripheral portion of the blank inwardly, and a second pressure ring around the male punch, the pressure rings having engageable end surfaces, the second pressure

ring being slidable relative to the female punch along the outer surface of the female punch in a direction away from the end surface of the peripheral wall to press the peripheral portion of the blank against said outer surface while the male punch holds the central portion in the recess of the female punch, means positioning the second pressure ring on forward movement of the die assemblies to achieve sliding of the second pressure ring relative to the female punch along the outer surface of the female punch, in said direction, only after the central portion of the blank has been pressed fully into the recess of the female punch, the first pressure ring having a foil catching edge adjacent said outer surface for curling the edge of the blank outwardly from said outer surface, said foil catching edge when the end surfaces of the pressure rings are engaged defining with the second pressure ring a foil curling cavity for forming an outwardly curled stiffening bead on the peripheral portion of the blank while the male punch holds the central portion in the recess, and means positioning the pressure rings to achieve sliding thereof relative to the female punch along the outer surface of the female punch in a direction opposite to said direction to catch

and curl the edge of the blank after the pressing of the peripheral portion of the blank against said outer surface, the first die assembly including a first gripping ring around the first pressure ring and the second die assembly including a second gripping ring around the second pressure ring, the gripping rings having end surfaces cooperable on forward movement of the die assemblies to grip the peripheral portion of the foil blank in a slip grip under which the peripheral portion is pulled inwardly without tearing, the positioning means for the second pressure ring comprising an upwardly facing rest on the second gripping ring, said rest supporting the second pressure ring, during the aforesaid gripping and pressing of the blank into the recess of the female punch, with the second pressure ring not protruding beyond the end surface of the second gripping ring.
